UNITED STATES PATENT OFFICE.

JOHN C. MCFARLAND AND WILLIAM J. LARKIN, OF CHICAGO, ILLINOIS;
SAID LARKIN ASSIGNOR TO SAID MCFARLAND.

FIREPROOF WINDOW.

SPECIFICATION forming part of Letters Patent No. 660,117, dated October 23, 1900.

Application filed July 7, 1899 Serial No. 723,035. (No model.)

To all whom it may concern:

Be it known that we, JOHN C. MCFARLAND and WILLIAM J. LARKIN, citizens of the United States, residing at Chicago, in the county of Cook and State of Illinois, have invented certain new and useful Improvements in Fireproof Windows, of which the following is a full, clear, and exact specification.

Our invention relates to that class of fireproof windows more especially intended for preventing fire from entering a building from without, and which are usually constructed with wire-glass set in metallic or fireproof swinging or pivoted sashes; and our invention has for its primary object to provide an improved construction of fireproof window of the described character which when closed will be fire and water proof.

With these ends in view our invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is a front elevation of a fireproof window constructed according to our improvements. Fig. 2 is a vertical sectional view thereof on a larger scale, showing the upper sash open in dotted lines, the lower sash being broken away. Fig. 3 is a vertical sectional view taken on the line 3-3, Fig. 1, intermediate parts being broken out for shortening the figure. Fig. 4 is a plan section taken on the irregular section-line 4-4, Fig. 1. Fig. 5 is a perspective view of parts of the sash and frame at the pivotal point on the right-hand side, and Fig. 6 is a similar view of the left-hand side.

The window-sill, or, more properly speaking, that part of the window-frame upon which the sill is formed, is composed of a single piece of metal, as shown at the bottom of Fig. 3, bent to give it the desired angles, and having along its top an upward, box-shaped bend 1, which forms the abutment-flange for the lower edge of the lower glass 2, 3 representing the putty or other substance for holding the glass in place. The glass may also be held by any suitable clips or other suitable

devices well known, but not shown. The upper edge of the lower glass 2 is seated against a flange or shoulder 4, formed on the division-bar, which extends across the window-frame and is secured at its opposite ends in any suitable way to the upright members of such frame. This division-bar is preferably composed of two pieces of sheet metal, as better shown in Fig. 3, which at its intermediate part is bent down to form the flange, while its two edges are turned outwardly to form lateral flanges 5 6. The upper side of the division-bar is composed of a single piece of metal whose edges are lapped over and around the flanges 5 6, as shown at 7, and on one side is carried upwardly in a vertical direction, and then downwardly and bent upon itself to form an upwardly-extending flange 8, and is then carried horizontally, as shown at 9, to form the top of the division-bar. This horizontal portion 9 is bent back under itself toward the left, thence downwardly, and again toward the right to form a flange 10, projecting laterally along one edge of the division-bar, such flange 10 being considerably above the portion 11, so as to constitute a groove or socket for the reception of a flange or lip 12, formed on a hood 13, carried by the lower side of the upper sash, which latter is pivoted by pivots 14 to the side members of the window-frame, as will be presently described. The lower member of the upper sash is preferably composed of a single piece of sheet metal whose one edge is bent laterally to enter into the formation of the flange 12 and thence upwardly past the flange 10, then horizontally across the top 9 of the division-bar, then upwardly and downwardly to form a stiffening-flange 15, which abuts against the flange 8 when the upper sash is closed and forms therewith a tight joint. From this flange 15 the metal is carried horizontally and thence upwardly to form a box-shaped flange 16, which constitutes the abutment-flange for the lower edge of the glass 17 of the upper sash, 18 being the putty on the other side of the glass. From the box-shaped flange 16 the metal is carried downwardly under the lower edge of the glass 17 and thence horizontally along itself, downwardly around the flange 10, and finally lapped over

its other edge and forms with the latter the flange 12, which in entering between the flange 10 and the bend 11 forms a joint that is sufficiently tight to be fire and water proof.

- 5 By referring to the lower side of Fig. 4 it will be seen that the side member of the upper sash from the pivot 14 downward is constructed in the same way as the bottom member, it being provided with a hood 19, which 10 extends from the pivot 14 down to the bottom member of the sash and is joined in any suitable way with the hood 13 and provided with an inwardly - turned flange 20 on one side and the stiffening-flange 21 on the other, as 15 well as with the glass abutment-flange 22, all of which parts are constituted and formed in the manner before described with reference to the bottom member of the upper sash in Fig. 3. This flange 20 of the side member 20 of the sash interlaps with a flange 23, secured to the side member of the window-frame, which is depressed, as clearly shown in Fig. 4, to form with the flange 23 a chamber or recess 24 for the reception of the flange 20, 25 thus making a tight sill for preventing the admission of fire and water. As a convenient and efficient means of attaching the flange 23 to the side member of the window-frame we form such side member with a vertical socket 25 by bending the metal of which the side member is constituted inwardly toward the wall and thence outwardly upon itself, so as to form one long lap 26 and a short lap 27 and constituting a narrow socket 30 in which an angle 28, formed on the flange 23, is inserted, the angle 28 going, preferably, to the inner end of the socket 27, and thus gaging the position of the flange 23.
- The side members of the window-frame are 35 the same on both sides and constructed in the manner already described from top to bottom or at least throughout the height of the pivoted sash; but the side members of the pivoted sash from the pivot 14 upward 40 are constructed in the manner shown at the top of Fig. 4, it being understood that the hood and flange before described for constituting the sill along the vertical edges must be so arranged that below the pivot the hood 45 moves outwardly or away from the flange, while above the pivot the flange moves away from the hood, and hence in one instance the hood is secured to the window-frame and in the other to the sash. It will also be appreciated that in one instance the sash moves in one direction and in the other in the opposite direction. Hence the sash from the pivot 50 upward is formed on one side, and the same side as the hood 19, with a straight flange 29, 55 which engages in a hood 30, secured to the side of the window-frame. This hood 30 is formed of a strip of metal bent in the shape of a double L, one flange 31 of which enters the vertical socket 27, formed in the side 60 member of the window-frame, as already described.

The side member of the sash from the pivot

14 upward is formed with the flanges 21 22, as before described; but its edges, instead of being bent to form three sides of a square, as before described with reference to the lower portion of Fig. 4, are carried out straight to form the flange 29 and thence lapped one around the other, as clearly shown in Fig. 4, to bind the edges together.

The pieces constituting the flange 23 and the hood 30 may be in two parts, if desired, and the edges of the angle-pieces 28.31 allowed to abut one upon the other in the sockets 27.

From the foregoing it will be understood that the side members of the pivotal sash are the same in construction and operation on both sides, but different above and below the pivotal point, as illustrated in Fig. 4.

The pivots 14 are preferably in the form of bolts, which are passed through the side members of the pivotal sash at a point above its center, so that the lower part of the sash will be the heavier and exert a normal tendency to close when released. It will also be clearly shown from Figs. 3 and 4 that the pivots 14 are arranged to one side of the central line of the side members of the sash. This is done for the purpose of reducing the arc described by the outer sides of the hoods 19, adjacent to the pivotal point, and thereby enabling us to project a lap 19^a up under the hood 30, secured to the frame, and to bring the end of such hood down closer to the pivot 14 and at the same time maintain the maximum swing or opening of the pivotal sash, a result which could not be accomplished excepting in the minimum degree were the pivot 14 located at the mid-transverse section of the sash members.

The pivot-bolts 14 pass through both sides of the hoods 19 at their upper ends, but, as shown in Fig. 3, the upper ends of the tongues or flanges 23 terminate a little below the pivot 14, so as not to interfere with the insertion of the bolts. The inner ends of the bolts pass through the members of the window-frame and may be secured in any suitable manner, as by a threaded block or nut 32, secured in the side member of the frame; also, if desired, the outer sides of the hoods 19 may be stiffened or reinforced by blocks 22, riveted or otherwise secured thereto.

The top horizontal member 34 of the window-frame may be exactly the same in construction and design as the side members, excepting that it has the cornice-pieces 35 on each face or side which projects up past the masonry; but it is provided with a socket 27^a, like the sockets 27 in the side members, and in the socket 20^a engages a tongue or flange 36, by means of which a hood 30^a, exactly the same in construction and arrangement as the hood 30, before described, is secured and supported on the frame and serves for the reception of a tongue or flange 29^a, formed along one side of the upper horizontal member of the pivotal sash. By this means it will be

seen that a perfect sill is also established along the top of the pivotal sash. This top horizontal member of the pivotal sash is preferably formed of a single strip of metal which has one fold bent downwardly to form the glass abutment-flange 37 and is then bent outwardly and upwardly to form a flange 38, which overlaps the top horizontal member of the window-frame. The strip is then carried downwardly along itself to the opposite side of the sash and finally bent around its other edge, as shown at 39, to secure the edges together and at the same time form the flange or tongue 29.

40 represents a vertical division-bar, which may be used when the glass employed is composed of a plurality of panes. This division-bar 40 connects the lower member of the pivotal sash with its upper member, and a similar bar may also be employed in the lower fixed sash, if desired; but in the example shown in the drawings such bar is omitted, a single pane being employed in the lower part of the window. This bar 40 consists of a single strip of metal bent to form a box-like body portion 41, which is stiffened by a flange 42, the edges of the strip being carried together between the panes 17 and one edge being lapped back upon the other, as shown at 43, to form a flange for the putty 44.

The pivotal window-sash may be held in its open position in the usual or any suitable way—such, for instance, as by means of a rod 45, attached at its upper end to the bolt 46 of a latch, which secures the window when closed, while the lower end of the rod may be secured to a hook 47 for holding the sash open.

Having thus described our invention, what we claim as new therein, and desire to secure by Letters Patent, is—

1. In a fireproof window the combination of a window-frame and a sash pivoted therein and one of said parts having a socket formed longitudinally therein, and a flange member and a hood member carried by said sash and frame and interlocking with each other for forming a tight joint between the frame and sash, one of said members having a tongue fitting in said socket for holding such member in place, substantially as set forth.

2. In a fireproof window the combination of a frame, a sash pivoted therein, flanges carried by the sash from the pivotal point upward, hoods carried by the frame from said pivotal point upward for receiving said flanges, hoods carried by the sash from the pivotal point downward and flanges carried by the frame from the pivotal point downward for engaging in the last said hoods, while the sash is closed, the lower hood extending within and lapping with the upper hood, substantially as set forth.

3. In a fireproof window the combination of a frame, a sash pivoted therein, a hood carried by the frame from the pivotal point upward, a flange carried by the sash from the

pivotal point upward for engaging in said hood, a hood carried by the sash from the pivotal point downward and a flange carried by the frame from the pivotal point downward for engaging in the last said hood, the last said hood being provided with a projection at its upper end extending above and lapsing with the lower end of the first said hood for making said hoods practically continuous when the sash is closed, substantially as set forth.

4. In a fireproof window the combination of a window-frame, a sash pivoted therein, said sash on one side from the pivotal point being provided with a flange and on the same side from the pivotal point with a hood and said window-frame being provided on one side at a point opposite said flange with a hood for receiving said flange and on the same side opposite the first said hood with a flange for receiving the latter, substantially as set forth.

5. In a fireproof window the combination of a window-frame having vertical slits or sockets formed therein, the tongues or flanges 28 31 engaging in said slits or sockets, weather-strip members carried by said flanges or tongues 28 31, and a sash pivoted in said frame and having weather-strip members overlapping and co-operating with said first weather-strip members, substantially as set forth.

6. In a fireproof window the combination of a window-frame having the vertical sockets 27 in the sides thereof, the flanges 28 31 engaging in said sockets, one of said flanges being secured to and carrying the flange 23 and the other having the hood 30, a sash pivoted in said frame and having a hood for engaging over said flange 23 and a flange for engaging in the said hood 30, substantially as set forth.

7. In a fireproof window the combination of a window-frame constructed of sheet metal and lapped inwardly upon itself to form a narrow socket, a weather-strip member having a tongue or flange fitted in and secured by said socket, a pivoted window-sash and a weather-strip member carried by said sash and co-operating with said first weather-strip member, substantially as set forth.

8. In a fireproof window the combination of a window-frame having its side members constructed with the vertical sockets 27, a window-sash pivoted in said frame, the flange 23 having the tongue or flange 28 and the flange 31 having the hood 30 inserted end to end in each of said vertical sockets and terminating at the pivotal point of said sash, a hood carried by the sash for engaging over the flange 23 and a flange carried by the sash for engaging in said hood 30, substantially as set forth.

9. In a fireproof window the combination of a window-sash having one of its members constructed of a single strip of sheet metal bent to form the flanges 21 22 and the hood 19 and having its edges lapped to form a flange

20, and a window-frame provided with a flange adapted to engage in said hood, substantially as set forth.

10. In a fireproof window the combination 5 of a pivotal sash having its side members constructed of a strip of sheet metal which from the pivotal point toward one end is folded upon itself to form the glass abutment-flange 22 and the hood 19 20 and from the pivotal 10 point to the other end to form the glass abutment-flange 22 and a straight flange 29 and a window-frame having weather-strip members for coöperating with said hood and flange, substantially as set forth.

15. 11. In a fireproof window the combination of a window-frame, a sash pivoted therein, said sash and frame having overlapping weather-strips extending past the pivotal point of the sash and overlapping one another 20 and the pivotal point of the sash arranged to one side of its vertical central line, substantially as and for the purpose set forth.

12. In a fireproof window the combination 25 of a window-frame, a pivotal sash therein, a division member connecting the side members of said frame together and being composed of two strips of sheet metal, one of which is bent to form the flange 4 for the abutment of the glass below and the other of 30 which has its edges lapped around the edges of the first said strip and bent upwardly and thence inwardly at 11, then upwardly and again outwardly to form the flange 10, thence back upon itself to form the top 9 of the division-bar, and a weather-strip member car-

ried by the sash and coöperating with said flange 10, substantially as set forth.

13. In a fireproof window the combination of a window-frame, a division-bar connecting the sides of said frame together and being 40 composed of two sheets or strips of metal, one of which is bent to form the glass abutment 4 and has its edges turned outwardly to form lateral flanges 5 6, and the other of which has its edges lapped around said flanges 5 6 and 45 thence carried upwardly on one side and inwardly to form the bend 11 and thence upwardly and outwardly and again inwardly to form the flange 10 and top 9 of the division-bar and thence upwardly and downwardly to 50 form the flange 8, and a pivotal sash having a weather-strip member coöperating with said flange 10, substantially as set forth.

14. In a fireproof window the combination of a window-sash, a plurality of panes of glass 55 therein, the division-bar 40 for supporting said panes consisting of a single strip of metal bent to form the box-like body 41 and squeezed together to form the flange 42 on one side of said box and squeezed together on 60 the opposite side of said box to form the flange 43, the edges of said strip being lapped one around the other and projecting between the panes of glass, substantially as set forth.
